(57) **CLAIM**

The ornamental design for a display screen with a graphical user interface, as shown and described.

DESCRIPTION

FIG. 1 is a front view of a first embodiment of a display screen with a graphical user interface showing our new design;

FIG. 2 is a front view of a second embodiment of a display screen with a graphical user interface showing our new design;

FIG. 3 is a front view of a third embodiment of a display screen with a graphical user interface showing our new design;

FIG. 4 is a front view of a fourth embodiment of a display screen with a graphical user interface showing our new design;

FIG. 5 is a front view of a fifth embodiment of a display screen with a graphical user interface showing our new design;

FIG. 6 is a front view of a sixth embodiment of a display screen with a graphical user interface showing our new design;

FIG. 7 is a front view of a seventh embodiment of a display screen with a graphical user interface showing our new design;

FIG. 8 is a front view of an eighth embodiment of a display screen with a graphical user interface showing our new design;

FIG. 9 is a front view of a ninth embodiment of display screen with a graphical user interface showing our new design; and,

FIG. 10 is a front view of a tenth embodiment of a display screen with a graphical user interface showing our new design.

The broken lines showing an electronic device illustrate environmental subject matter, whereas the broken lines showing display screen and elements of the graphical user

(Continued)

interface illustrate portions of the article. No subject matter depicted in broken lines forms part of the claimed design.

1 Claim, 10 Drawing Sheets
